UNITED STATES PATENT OFFICE.

ROBERT N. ROCKWELL, OF PEABODY, KANSAS.

WIND-WHEEL.

SPECIFICATION forming part of Letters Patent No. 292,057, dated January 15, 1884.

Application filed June 29, 1883. (No model.)

To all whom it may concern:

Be it known that I, R. N. ROCKWELL, a citizen of the United States, and a resident of Peabody, in the county of Marion and State of 5 Kansas, have invented certain new and useful Improvements in Wind-Wheels; and I do hereby declare that the following is a full, clear, and exact description of the invention, which will enable others skilled in the art to 10 which it appertains to make and use the same, reference being had to the accompanying drawings, which form a part of this specification, and in which—

Figure 1 is a perspective view of my improved wind-wheel. Fig. 2 is a perspective of the hub of the same, showing four vanes inserted, illustrating the manner of inserting the vanes; and Figs. 3, 4, 5, and 6 are detail views of the several parts of the wheel.

20 Similar letters of reference indicate corresponding parts in all the figures.

My invention has relation to wind-wheels; and it consists in the improved construction and combination of parts of the vanes and 25 their fastenings in a wind-wheel, as hereinafter more fully described and claimed.

In the accompanying drawings, the letter A indicates the drive-shaft of the mill, the outer portion of which shaft is square, having 30 an outer screw-threaded end, upon which a nut, B, fits and turns, while the inner end of the square portion is provided with a flange, C, projecting laterally.

The square end of the shaft fits into a square 35 central perforation, D, in a hub or disk, E, the edge of which has a number of inclined or spiral mortises, F, around its periphery, into which mortises the inner ends of the vanes G fit. The vanes G are longer than the supplemental vanes, H, which are placed with their 40 ends between the inner ends of the longer vanes, resting with their inner ends against the portion of the rim of the hub, between two mortises, the vanes G being as much 45 longer than the vanes H as the depth of the mortises.

A disk, I, having a square central aperture, J; which fits over the square end of the shaft, and, being of a larger diameter than the

hub, is placed upon the inner end of the 50 square portion of the shaft, bearing against the flange C with its rear side, while its frontward-facing side bears against the rear edges of the vanes.

A disk, K, of the same diameter as disk I, 55 and having a sharp inwardly-projecting flange, L, V-shaped in section, fits with its central perforation, M, over the screw-threaded end of the shaft, and may be pressed in against the front edges of the vanes by means of 60 the nut N, fitting and turning upon the screw-threaded end of the shaft, and by means of a number of screw-bolts, O, passing through a series of perforations in the rims of the disks and through the vanes, securing the disks 65 and pressing them tightly against the edges of the vanes. It will be seen that in this manner every vane need not be bolted or otherwise secured to the hub or the disks, the sharp inwardly-projecting flange cutting into the 70 edges of the vanes, holding them fast.

For the purpose of securing the outer ends of the vanes, the latter are fastened with their outer ends to an annular rim or flat ring, P, which prevents the ends from becoming bent 75 out of the plane of the other vanes, and preventing the vanes which are inserted between the vanes inserted into the spiral mortises from working out and becoming loose.

Having thus described my invention, I claim 80 and desire to secure by Letters Patent of the United States—

1. The combination of the hub having the spiral mortises in its periphery, the longer vanes fitting with their inner ends into the 85 said mortises, the shorter vanes fitting with their inner ends into the spaces between the ends of the longer vanes, and means for holding the said vanes in position, as and for the purpose shown and set forth. 90

2. The herein-described wind-wheel, consisting of the shaft having the outer square portion and the outer screw-threaded end provided with a fastening-nut, the hub having the spiral mortises in its rim, and having 95 the square central perforation, the longer vanes, the shorter vanes, the inner smooth disk, the outer disk having the annular sharp

inwardly-projecting flange upon its inner face, the bolts passing through the edges of the disks and through the vanes, and the outer flat ring or annular rim fastened to the outer 5 ends of the vanes, all constructed and combined as and for the purpose shown and set forth.

In testimony that I claim the foregoing as my own I have hereunto affixed my signature in presence of two witnesses.

ROBERT N. ROCKWELL.
